UNITED STATES PATENT OFFICE.

WHITCOMB L. JUDSON, OF MINNEAPOLIS, MINNESOTA, ASSIGNOR TO THE JUDSON PNEUMATIC RAILWAY COMPANY, OF SAME PLACE.

MECHANICAL MOVEMENT.

SPECIFICATION forming part of Letters Patent No. 402,674, dated May 7, 1889.

Application filed November 15, 1888. Serial No. 290,879. (No model.)

To all whom it may concern:

Be it known that I, WHITCOMB L. JUDSON, a citizen of the United States, and a resident of the city of Minneapolis, county of Hennepin,

5 State of Minnesota, have invented a certain new and useful Mechanical Movement, of which the following is a specification, reference being had to the accompanying drawings.

10 My invention is especially designed for use in connection with a street-railway system, but is capable of universal application wherever it is desired to turn a rotary into rectilinear motion.

15 It consists of the construction hereinafter fully described, and particularly pointed out in the claims.

20 In the drawings, like letters referring to like parts throughout, Figure 1 is a side elevation of my preferred construction; Fig. 2, a cross-section or end view of the same; Fig. 3, a plan of the driving-drum and friction-wheels partly detached from their supporting-frame. Fig. 4 is a side elevation of a modified construction; Fig. 5, an end view or cross-section of the construction shown in Fig. 4; Fig. 6, a plan of the driving-drums and friction-wheel detached from their supporting-frames, and Fig. 7 is a plan of a part of the supporting-frame in which the friction-wheel is mounted.

25 In the construction shown in Figs. 1, 2, and 3 I use a single driving drum or shaft and a pair of traveling friction-wheels engaging therewith at an angle to its axis.

30 In the construction shown in Figs. 4 to 7, inclusive, I use a pair of parallel driving-drums, continuously revolving in the same direction, and a single traveling friction-wheel engaging with both drums at an angle 40 to their axes.

If the friction wheel or wheels are placed at a right angle to the driving drum or drums, they will not travel lengthwise thereof. If they take any other than a position at right angles 45 to the driving-drums and the parallelism of their axes be preserved, they will travel in one direction or the other along the driving drum or drums.

Referring now to the various figures, I have 50 shown the motion as applied to reciprocate a

small car or carriage on a definite track—such, for example, as might be used in a planing-machine, a saw-mill, or other machines wherein a reciprocating motion might be desired.

55 A is a driving-drum in fixed supports B. As shown, these fixed supports are cross-bars secured to upright posts C on the opposite sides of the shaft.

D are girders mounted on the tops of the 60 vertical posts, and E are rails bolted to the girders D. F is a small car or carriage whose wheels rest on the rails E. To this car is secured a spider or yoke, G, provided at its outer extremities with circular rims G' G''. 65 These rims are provided on their outer surfaces with inwardly-projecting flanges g.

H are revoluble heads mounted in the rims G' G'' and provided with journal-bearings h and plates h' overlapping the flanges g.

70 K are traveling friction-wheels mounted in the revoluble heads H.

L is a rock-shaft on the car F, and is provided with cranks L' and L'', opposite to each other. From these cranks extend connections 75 l and l', respectively, to the revoluble heads H.

M is a hand-lever on the rock-shaft L. M' is a notched segment adjacent thereto.

M'' is a pawl on the lever M, for engaging 80 with the notched segment M'. By means of the lever M and its connections the revoluble heads H may be moved in opposite directions in the supporting-rims G' and G'', thus varying the angle of the friction-wheels K to the 85 driving-shaft A, while preserving the parallelism of the axes and the peripheries of said wheels.

90 As shown, the yoke or spider G is a curved spring-bar. For the purpose of obtaining a variable traction suitable to the load, a right-and-left screw, N, passes through corresponding nuts on the outer ends of the yoke G and is provided with a hand-lever, N', extending within reach of the operator of the car. 95

N'' is a notched segment adjacent to the lever N'.

N''' is a pawl on the lever N' for engaging with the segment N''.

Referring now to the modification shown in 100

Figs. 4, 5, 6, and 7, P P' are a pair of parallel driving-drums similar to the driving-drum A, arranged adjacent to each other and continuously revolving in the same direction. Q is a swiveled yoke mounted on the car F, provided with the journal-bearing q. R is a single traveling friction-wheel mounted in the bearings q. S is a segment-plate provided with a curved groove, S', secured to a part of the car 10 adjacent to the swiveled yoke Q. T is a cross-head or movable block mounted in the groove S'. U is a hand-lever fulcrumed in the block T intermediate its extremities, and pivotally connected at its inner end to the yoke Q. V 15 is a coiled spring encircling the vertical shaft of the yoke intermediate the car-frame, or a boss, W, on the same, and the bifurcated arms of the yoke.

It is evident that by the lever U and its connections the yoke may be swung through the arc of a circle and the friction-wheel be made to take any desired angle to the parallel driving-drums; hence the car may be made to stand still or to travel in either direction 25 lengthwise of the driving-drums at a variable speed.

The advantage of using one device of one kind opposed to two of the other is that thereby a wedging or crowding action is secured, 30 giving far better frictional contact and a resultant of forces substantially in a straight line without other limiting-guides. The driving-drums may be driven in any suitable way from a source of power.

In the drawings the drum or drums have been shown as the propeller, and the friction wheel or wheels as the traveler; but it will be readily understood that the reverse arrangement will work. A rectilinear motion of 35 the friction-wheels will impart a rotary motion to the drums; or, if the friction-wheels be mounted in fixed supports and made to rotate and the drum or drums in movable supports, the former being at an angle to the axis of the latter, the drums will be made to 40 travel in a right line. In other words, the wheels and the drums are interchangeably propellers or travelers. It should also be noted that the power is convertible into speed 45 or the speed into power at will. If the propeller be driven with uniform power and

speed, it will take effect on the traveler more in speed or more in power, according to the angle of the wheel or wheels to the drum or drums, which angle is variable at will. In 55 other words, the construction is practically that of a screw and nuts of a pitch variable at will, frictional contact taking the place of the positive thread. The drums are threadless screws, and the wheels are nuts following 60 imaginary lines thereon by frictional contact, the pitch of which and the direction of which (from right to left) are variable at will.

What I claim, and desire to secure by Letters Patent of the United States, is as follows: 65

1. The combination of cylindrical-drum and friction-wheel devices capable of angular engagement with each other, there being one device of one kind and two of the other, and the angles of engagement variable at will, 70 whereby the rotation of the device or devices of one kind gives a rectilinear movement, the speed of which is proportionate to the angle of engagement to such of the other as are engaged thereby, substantially as described. 75

2. The combination of cylindrical-drum and friction-wheel devices capable of angular engagement with each other, there being one device of one kind and two of the other, such as are employed of one kind being 80 mounted in fixed, and such as are employed of the other in movable, supports, substantially as described.

3. The combination, with a cylindrical driving-drum, of two friction-wheels capable of 85 angular engagement therewith, the said wheels being mounted in movable bearings, whereby their angles of engagement with said drum may be varied, substantially as described. 90

4. The combination, with a cylindrical driving-drum mounted in fixed supports, of two friction-wheels capable of angular engagement therewith on opposite sides, said wheels being mounted in a movable support and in 95 movable bearings in said support, substantially as described.

WHITCOMB L. JUDSON.

In presence of—

JAS. F. WILLIAMSON,
EMMA F. ELMORE.
